UNITED STATES PATENT OFFICE.

JACOB J. HONECKER, OF CLEVELAND, OHIO.

DESIGN FOR A SPONGE-CASE.

SPECIFICATION forming part of Design No. 28,118, dated January 4, 1898.

Application filed October 5, 1897. Serial No. 654,185. Term of patent 14 years.

To all whom it may concern:

Be it known that I, JACOB J. HONECKER, a citizen of the United States, residing at Cleveland, in the county of Cuyahoga and State of Ohio, have invented and produced a new and original Design in Sponge-Cases, of which the following is a specification, reference being had to the accompanying drawing, in which an elevation of the design is shown as it appears when in use.

In the drawing the leading or material feature of my design consists in the series of inclined ornamental members A, disposed to constitute, together with the several ornamental borders above and below and the standard, a complete design. Thus it will be seen that said members A are fashioned with borders 2 of their own and transparent faces

3 within the borders at their front and figured sides 4 at their rear. These several distinct embodiments A of the design are disposed in series around a plain central standard 5 at an inclination of about forty-five degrees to the said standard, giving the entire design an unfolded but harmonious appearance.

What I claim is—

The design for a sponge-case, substantially as shown and described.

Witness my hand to the foregoing specification this 25th day of September, 1897.

JACOB J. HONECKER.

Witnesses:

H. T. FISHER,
R. B. MOSER.
